UNITED STATES PATENT OFFICE

PETER EUFINGER, OF FRANKFORT-ON-THE-MAIN, AND WILHELM QUANTE, OF
WUPPERTHAL-ELBERFELD, GERMANY

MACHINE FOR SPLICING CABLES

Application filed May 28, 1931. Serial No. 540,772, and in Germany June 16, 1930.

The invention relates to an improved machine for splicing cables. Machines of this type known up to the present show the drawback, that they will work too slowly, being in many respects too inconvenient, in particular the handling of the known machines inside of the cable pit is peculiarly troublesome because of their size and unwieldiness. With the known types of machines the device for the splicing of the cable strands consisted of so-called winding hooks, into which were inserted the ends of the wires to be spliced, after the prior removal of the insulation by hand. The splicing is effected by turning the winding hooks. After a few revolutions the ends of the splicing portions were torn off by the said winding hooks.

The throwing out of the spliced wires and the covering by means of the paper rolls serving as an insulation was effected automatically and at such a speed that the operator in attendance had no chance of making out, whether or not the splicing was carried out properly. There was the danger, that an insufficient or fragile splicing was hidden by the insulating tube, without the operator being able to notice this deficiency. The mounting of the known machines besides, was very circumstantial for the handling thereof, since the machines were secured by stirrups to the cable and owing to their own weight and that of the stirrups they had no sufficient support in view of the considerable forces applied during the operation.

The machine according to the invention obviates the drawbacks of the known machines, in that it will execute the several steps of operation quickly and neatly. In addition the operator is able to supervise each single working step. The mounting of the machine according to the invention is effected in a safe manner.

The main advantage of the machine according to the invention consists in that the ends of the wires to be spliced will be stripped of their insulation by a common device after having been inserted into the machine, so that as already stated above, the tiresome

removal of the insulation on each single wire is wholly dispensed with.

The automatic pulling over of the paper tubes is obviated in the machine according to the invention since this operation will easily give rise to trouble and a control of the finished splice is only possible, if the said tubes or rolls or sleeves are pulled over by hand.

A further advantage of the invention consists in that the ends of the wires introduced into the machine are cut to a certain length, while the removal of the insulation will take place later on. Thereupon the splicing of the ends of the wires is carried through. After the splice is finished the spliced portions are cut to a definite length.

A further advantage of the invention is to be seen in the simple construction of the device serving for cutting off the spliced portions. Said device is approached towards the cable and operated for cutting by actuating a single lever only. It is suitable to move the said lever in both directions, once for approaching the device to the cable and in the other direction for the purpose of actuating the said device.

A considerable advantage of the invention consists in the steps of adjusting the machine in respect of the cable. In this manner it is possible to distribute the various splicing points of the many pair of strands of the cable uniformly over a distinct length of the cable, so that a relatively slight thickening of the cable at the splicing spot will occur. On account of the adjusting device according to the invention the machine is adapted to be moved vertically and parallelly to the cable. Owing to a special advantage of the invention the said machine may be raised or lowered besides.

According to a further feature of the invention the machine rests upon a frame, which is secured within the cable well by means of tensioning devices. The said frame will require a relatively small space and it can be secured extraordinarily safely within the cable well, ensuring a reliable operation of the machine.

An embodiment according to the invention is illustrated by way of example in the drawings wherein

Figure 1 is a plan view of the frame,

Figures 2 and 3 are side views respectively of the said frame, and

Figures 4 to 10 show details in elevation.

Hereinafter the machine is disclosed in detail. Other features of the invention will follow from the specification and claims.

Figures 1 to 3 represent a mounting frame for the machine, rendering possible a safe mounting thereof within the cable well. Figures 4 to 6 show details of the mounting frame, constituting a variation of a portion of the frame represented in Figures 1 to 3. The machine proper is illustrated in Figures 7 to 10.

The mounting of the machine will now be described. The frame illustrated in Figure 1 in plan and in Figures 2 and 3 in side elevation, consists of the rails 1 and 2 secured within the cable well vertically to the cable, and of the bars 10 and 11 displaceably arranged on said rails. The rails 1 and 2 are placed under tension by screwing out the screw bolts 3 to 6 within the cable well. The cable rests upon the rails and in a given case it can be bound to said rails.

The bars 10 and 11 respectively, running thus parallelly to the cable, serve for the guiding of the splicing machine in the right or left direction as described hereinafter. The bars 10 and 11 are rigidly connected with one another by means of transverse members 7, in the center of which are provided screws 8 and 9, serving for the fixing. Preferably the rails 1 and 2 consist of tubes having a rectangular cross-section, the said screws 8 and 9 are suitably provided with heads, as shown by part 14 in Figure 1. When tightening the nuts the opposite sides of the head are forced towards and against the walls of the said tubes 1 and 2, so that a secure connection is effected between the bars 10, 11 and 1, 2 respectively. The connection between the tensioning screws and the tubes is suitably effected by means of insert members 15, riveted to the tubes 1 and 2 and provided with a threaded hole for the reception of the bolts. As stated above the machine is adapted to be displaced parallelly to the cable. It is preferable to provide one of the bars 10 or 11 with notches in order to easily effect a displacement by a certain amount, rendering possible in consequence an always equal shifting of the splicing spots. In Figure 3 balls 12 are shown, which belong to an arrangement of notches provided on the splicing machine.

With the arrangement according to Figures 1 to 3 the machine is adapted to be displaced vertically and parallelly to the cable in the plane of the frame. A further arrangement is represented in Figures 4 to 6

rendering it possible to lift the splicing machine out of the said frame and to displace it in a given case in respect of the plane of the frame. It is supposed in this instance, that the rails 1 and 2 possess a U-shaped cross-section. The bars 10 and 11 carrying the machine are connected by way of a special arrangement, shown in section in Figures 4 and 5 and in plan in Figure 6. The bars 10 and 11 are connected with one another by means of transverse members, of which the left one in Figure 5 is designated by 16. A corresponding transverse member is arranged at the right hand side of the bars 10 and 11 and it is connected to the bar 2 by an arrangement similar to that illustrated in Figures 4 to 6. The transverse member 16 carries a nut 17 through which one of the spindles, 24, is screwed. The said spindle 24 is journaled in the bearing block 23 and is turned by means of a crank 25. The bearing block 23 is pivotally arranged on the bolt 19 so that a swinging in the plane passing through the bars 10 and 11 is rendered possible. The bolt 19 is carried by a bearing block 18, which is displaceably arranged on the bar 1 and can be fixed thereon. The fixing is done by means of the set screw 22.

When tightening the said screw 22 the bearing block is tightly pressed upon the bar 1 over the eyes 20 and 21, so that a displacement is rendered impossible. The fixation in respect of a turning of the block or support 23 receiving the spindle 24 is effected by means of the handled nut 26 being tightened. It follows from this illustration that the bars 10 and 11 may be raised or lowered by operating the crank 25 and a corresponding crank provided on the right side, and that an inclination of the plane passing through the bars 10 and 11 after the release of the handled nut 26 is rendered possible.

After the mounting and the adjustment of the splicing machine in respect of the cable has been described, the machine proper is now to be explained with the aid of Figures 7 to 10.

A portion of the machine is formed by the bed 27 arranged on the bars 10 and 11 parallelly displaceable in respect of the cable. On the bed 27 is displaceably arranged a carriage or slide 34, carrying the winding tongues 30 to 33. The carriage 34 can be displaced vertically to the cable. Bolts 28 and 29 secured to the bed 27 serve as guiding means. The sleeves 35 and 36 form part of the carriage 34. Besides the winding tongues the machine is fitted with two additional devices to be operated by hand, serving for cutting off the strands or the spliced spots respectively.

One of the cutting devices consisting of the knives 37 and 38 serves for cutting off the ends of the wires to be spliced to a certain length, and it is arranged on the carriage 34.

The second cutting means comprising the knives 39 and 40 is journaled in the bed 27 of the machine and serves for cutting off the finished splicings. This second cutting means is adapted to be let down and prior to its operation it is caused to approach the wires. This cutting means is illustrated in Figure 10 in both its positions. The position shown in hatched lines corresponds to the position of rest or inoperative position. Prior to its operation the arrangement is shifted to the position shown in full lines. As follows from Figures 7 and 10, the cutting device can be swung about the bolts 41 and 42 mounted in the bed 27.

For the purpose of operating the machine three handles are provided. The handle 43 serves for actuating the splicing device, the handle 44 for manipulating the cutting device for the protruding wire ends and the handle 45 for operating the cutting device for the spliced portions.

The operation of the machine according to the invention is described hereinafter.

After the bars 10 and 11 are removed into the correct position in respect of the cable, the bed 27 is fixed on the bars 10 and 11 by tightening the screw 46.

It is suitable to choose such a position of the bed that the ball 12 will drop into a notch on the bar 11 (confer Figure 3). The machine represented in the drawings is adapted for the simultaneous splicing of four pair of strands of wire or the like. Therefore eight wires must thus be placed into the machine. The first two wires are passed through the opening 47 and the next pair of wires through the openings 48 to 50. Here the winding tongues 30 to 33 are at first opened and the carriage 34 is shifted towards the front as far as possible (see the representation in dotted lines in Figure 9). Each winding tongue consists of two shanks, of which the lower one is stationary while the upper one is adapted to be turned up. The said winding tongues carry out two operations, namely the removal of the insulation and the splicing. The knife-edges 51 and 52 (Figure 9) of the winding tongues consist of steel and are exchangeable. Each edge is provided with two recesses, into which the wires are placed. In order to render possible the adjustment to different thickness of the wires, the upper jaw or edge 51 may be adjusted by means of the screw 53. Additional screws 54 and 55 serve for securing the edge. For the purpose of closing the winding tongues cam members 56 are provided which actuate latching slides 56a. A pin 56b is fixed to the lower shank of each winding tongue and projects up through an opening in the companion shank. The upper end of this pin is provided with a notch in which the slide 56a engages when the parts are to be held together in closed position.

By placing the individual wires in guiding grooves, of which one in Figure 7 is designated by 57, said wires will be placed at the same time into the winding tongues. The ends of the wires are held fast by means of springs, for instance 58, provided on the front of the carriage 34. In order to save the operator from becoming hurt by the said springs, the latter are covered by a protective metal sheet 59. The latter is suitably of U-shape (see Figure 9) and provided with transverse slots at the places in which the holding springs are arranged.

The second working step comprises the closing of the four winding tongues 30 to 33.

The third operation consists in the cutting off of the wire ends placed into the machine to a suitable length, which will not interfere with the subsequent working steps. On operating the handle 44 the knife 38 is displaced towards the stationary knife 37, so that the remaining ends of all eight strands protruding from the machine are cut off. In order to keep the force to be exerted on the handle 44 within reasonable limits even if strong strands of cable are used, the individual cutting edges of the knives 38 are arranged in staggered relation to each other, ensuring that one wire after the other is being cut off. After the release of the handle 44 the knife 38 will return under the action of the spring 60 into its inoperative position.

The fourth working step consists in providing for the removal of the insulation. For that purpose the carriage 34 is pulled towards the operator. During this movement all strands are freed from their insulation and the insulating material stripped off drops down. At the third working operation the crank 43 is turned round once for the purpose of splicing. The drive of the four winding tongues is effected in the following manner: By means of the crank 43 the gear wheel 61 is driven, which later meshes with the pinions 62 and 63 rigidly mounted on the shafts of the winding tongues 31 and 32. The pinions 64 and 65 of the winding tongues are driven by way of the gears 66 and 67. The ratio of transmission between the gear 61 and the pinions is so chosen, that during a full revolution of the gear 61 the pinions will carry out so many full revolutions as will be required for carrying out the splicing. In the inoperative position of the crank 43 the gear wheel 61 is positively locked by means of a notch, or catch, which latter, as will be seen from Figure 9, comprises a ball 70 under spring action, which ball in its position of rest will drop into a recess of the gear wheel 61. The spring casing 68 is sunk into the casing 69 of the machine. In operation the device is suitably located so that the opening of the said tongues and the introduction of the wires can be carried out easily.

The fifth working step consists of the actuation of the handle 45. The latter can be moved into two directions, namely at first it must be depressed vertically and subsequently displaced towards the left hand side. The lever 71 actuated by the handle 45 is journaled in the device for cutting off the spliced portions, by means of a bolt 72. On depressing the lever 71 (see Figure 10) the cutting device is moved towards the wires, whereby the said cutting device is swung about the bolts 41 and 42. An operation of the cutting knives during this movement is not as yet possible, since the lever 41 is guided along the face 73 of the cast body. When the knives 39 and 40 have reached the proper position in respect of the wires, that is to say, when the parts to be spliced lie already in the recesses of the knives, the lever 41 will engage the stop 74. At the same time the lever 41 leaves the face 73, so that it can be moved now towards the left hand side against the action of the spring 75. During this movement the knife 40 is displaced in respect of the stationary knife 39, so that the spliced parts are cut off, that is to say in succession, since both the knife 40 and the knife 38 possess knife-edges arranged in staggered relation to each other. When releasing the handle 45 the lever 71 under the action of the spring 75 will move towards the right side at first and subsequently to the top in its inoperative position in consequence of the gravity of the cutting device.

The splicings are now finished and it is only necessary now to pull the insulating tubes, which were stripped over the strands of one end of the cable already prior to the introduction of the wires in the machine, over the spliced portions in order to insulate the latter.

The making of the next splice is carried out in the same manner. After a number of splices have been finished the bed 27 will be displaced parallelly to the cable on the bars 10 and 11 either to the right or left hand side up to the next catch on the bar 11, in order to prevent the cable from growing too thick at the respective place. A further distribution of the individual splices can be effected through raising or lowering the machine. As described above the splicing machine according to the invention can be brought into any desired position in respect of the cable, so that no longer as was customary up to the present time, the individual wires are passed to the machine, but that the machine is approached to the wires.

The various features of the invention are summarized in the appended claims.

We claim:

1. Cable splicing machine of the character described comprising in combination means for placing the wires into the machine, winding tongues having means for removing the

insulation from said wires prior to splicing, gear means for driving the winding tongues and locking means for locking the gear driven by said driving means in a definite position, said locking means consisting of a ball catch 70 having a spring casing situated in the casing of the machine, the said gear means being provided with a recess, into which the ball drops.

2. Cable splicing machine of the character 75 described comprising in combination means for placing the wires into the said machine, common means for removing the insulation from said wires prior to splicing, means for cutting the wires introduced into the machine to a handy length prior to removing the insulation therefrom, means for holding the wires until they are cut off, said means being arranged in front of said cutting means, and a protective cover over said holding means. 80

3. Cable splicing machine of the character described comprising in combination means for placing the wires into the said machine, common means for removing the insulation from said wires prior to splicing, a cutting 90 device serving for cutting the finished spliced portions and adapted to be lowered, and means for approaching said cutting means to the wires only after removal of the insulation and after splicing. 95

4. Cable splicing machine of the character described comprising in combination means for placing the wires into the said machine, common means for removing the insulation from said wires prior to splicing, a cutting 100 device serving for cutting the finished spliced portions, and means movable in two directions vertically to one another and adapted to actuate said cutting means, which latter is approached to the wires in one direction and caused to be operated by moving said means in the opposite direction. 105

5. Cable splicing machine of the character described comprising in combination means for placing the wires into the said machine, common means for removing the insulation from said wires prior to splicing, a cutting 110 device serving for cutting the finished spliced portions and means movable in two directions vertically to one another and causing the cutting device to swing around an axis being parallel to the cable. 115

6. Cable splicing machine of the character described comprising in combination means for placing the wires into the said machines, common means for removing the insulation from said wires prior to splicing, a cutting 120 device serving for cutting the finished spliced portions and means for locking the said cutting device until the latter is approached to the wires. 125

7. Cable splicing machine of the character described comprising in combination means for placing the wires into the said machine, common means for removing the insulation 130

from said wires prior to splicing, a cutting device, locking means for said cutting device and a guide for said driving means provided on the frame of the machine and actuating said locking means.

8. Cable splicing machine of the character described comprising in combination means for placing the wires into the said machine, common means for removing the insulation from said wires prior to splicing, a cutting device, locking means for said cutting device, a guide for the driving means arranged on the frame of the machine and actuating said locking means and means for releasing said locking means, causing the cutting device to return automatically to its inoperative position.

9. Cable splicing machine of the character described comprising in combination means for placing the wires into the said machine, common means for removing the insulation from the said wires prior to splicing, a frame carrying the machine and adapted to be secured in a cable well, and supporting means for said frame whereon the frame is movably mounted.

10. Cable splicing machine of the character described comprising in combination means for placing the wires into the said machine, common means for removing the insulation from the said wires prior to splicing, a frame carrying the machine and means for displacing said splicing machine in the plane of the frame vertically and parallelly to the cable.

11. Cable splicing machine of the character described comprising in combination means for placing the wires into the said machine, common means for removing the insulation from said wires prior to splicing, a frame carrying the machine, means for vertically displacing said splicing machine in the plane of the frame and means for locking the said frame and machine against vertical displacement.

12. Cable splicing machine of the character described comprising in combination means for placing the wires into the said machine, common means for removing the insulation from said wires prior to splicing, a frame carrying the machine, means for displacing said splicing machine and a plurality of catches arranged on the cable for the moving of the said machine to the right and left and parallelly to the said cable.

13. Cable splicing machine of the character described comprising in combination means for placing the wires into the said machine, common means for removing the insulation from said wires prior to splicing, a frame carrying the machine, means for displacing said splicing machine and a ball under spring action serving as catch.

14. Cable splicing machine of the character described comprising in combination means for placing the wires into the machine,

common means for removing the insulation from the said wires prior to splicing, a frame carrying the machine, means for displacing said splicing machine vertically in the plane of the frame and means for lifting the machine from the plane of the said frame.

15. Cable splicing machine of the character described, said machine having a cable well provided with holding rails and comprising in combination means for placing the wires into the said machine, common means for removing the insulation from said wires prior to splicing, a frame carrying the machine and including rails along which the body of the machine is movable, said rails serving as guides, means for displacing said splicing machine along said guiding rails, and means for adjusting the rails serving for the guiding of the machine in respect of the holding rails mounted in the cable well.

16. In a cable splicing machine, means for positioning pairs of wire ends in the machine, winding tongues for engaging and twisting together the wires of the respective pairs, and insulation stripping means carried by said tongues.

17. In a cable splicing machine, means for positioning pairs of wire ends in the machine, winding tongues for engaging and twisting together the wires of the respective pairs, insulation stripping means carried by said tongues, means for cutting the wires to length prior to splicing, and means for cutting the spliced pairs of wires to predetermined lengths.

18. In a cable splicing machine, a carriage mounted for movement longitudinally of a wire cable, means on the carriage for positioning pairs of wire ends in position for twisting together, winding tongues mounted on the carriage to engage and twist together the wires of the respective pairs, and insulation stripping means carried by said winding tongues.

19. In a cable splicing machine, a carriage mounted for movement longitudinally of a wire cable, means on the carriage for positioning pairs of wire ends in position for twisting together, winding tongues mounted on the carriage to engage and twist together the wires of the respective pairs, insulation stripping means carried by said winding tongues, means for cutting the wires to length prior to splicing, and means for cutting the spliced pairs of wires to predetermined lengths.

20. In a cable splicing machine, means for positioning pairs of wire ends in the machine, winding tongues for engaging and twisting together the wires of the respective pairs, insulation stripping means carried by said tongues, and gearing for simultaneously operating said winding tongues and thereby causing simultaneous stripping of the insulation from all the wires.

21. In a cable splicing machine, a carriage mounted for movement longitudinally of a wire cable, means on the carriage for positioning pairs of wire ends in position for twisting together, winding tongues mounted on the carriage to engage and twist together the wires of the respective pairs, insulation stripping means carried by said winding tongues, and gearing for simultaneously operating said winding tongues and thereby causing simultaneous stripping of the insulation from all the wires.

22. In a cable splicing machine, a winding tongue consisting of a pair of jaws hinged together at one end to open and close, and coacting insulation stripping knives carried by the free ends of said jaws.

23. In a cable splicing machine, a winding tongue consisting of a pair of jaws hinged together at one end to open and close, coacting insulation stripping knives carried by the free ends of said jaws, and means to secure the knives adjustably on said jaws.

24. In a cable splicing machine, a winding tongue consisting of a pair of jaws hinged together at one end to open and close, coacting insulation stripping knives carried by the free ends of said jaws, means to secure the knives adjustably on said jaws, and coacting latch means carried by said jaws to secure the jaws releasably in closed position.

In testimony whereof we affix our signatures.

PETER EUFINGER.
WILHELM QUANTE.
